HIGH-PRESSURE, ELECTRICALLY ACTUATED, FLUID VALVE

Robert S. Keane, Placentia, Calif., assignor to International Research Corp., Anaheim, Calif., a corporation of California

Filed Mar. 25, 1966, Ser. No. 1,632

Term of patent 14 years

(Cl. D23—19)

FIG. 1 is a side elevation of a high-pressure, electrically actuated, fluid valve showing my new design;

FIG. 2 is an elevation thereof as viewed from the right of FIG. 1;

FIG. 3 is an elevation thereof as seen from the side opposed to that shown in FIG. 1;

FIG. 4 is an elevation thereof as viewed from the left of FIG. 1;

FIG. 5 is an end elevation thereof as seen from the top of FIG. 1;

FIG. 6 is an elevation thereof as seen from the bottom of FIG. 1;

FIG. 7 is a sectional view thereof taken on the line 7—7 of FIG. 1; and

FIG. 8 is an elevational view corresponding to FIG. 1 showing a modified form thereof.

The dominant features of the design reside in the portions shown in full lines.

I claim:

The ornamental design for a high-pressure, electrically actuated, fluid valve, as shown and described.
